UNITED STATES PATENT OFFICE

WILLIAM D. FERRIS, OF STERLING, ILLINOIS, ASSIGNOR TO FRANTZ MANUFACTURING COMPANY, OF STERLING, ILLINOIS, A CORPORATION OF ILLINOIS

GARAGE-DOOR CONSTRUCTION

Application filed May 21, 1928. Serial No. 279,382.

This invention relates to sliding and sectional doors of that kind in which a plurality of door sections are hinged together and provided with hangers to travel on an overhead track, and more particularly to doors of this kind that are required to slide or travel around a curve in the track upon which the hangers are mounted, whereby the entire door structure is moved out of the doorway of the garage or other building and around the curve into position at one side of the building, and within the building itself, thereby to fully open the doorway.

Generally stated, therefore, the object of the invention is to provide an improved construction and arrangement, particularly of the track structure upon which the door hangers travel, whereby a swinging door section may swing inward a distance until it is in position to lead the other sections around the curve in the track and into position at one side of the building, and whereby the swinging door section is always supported against sagging, and in addition is always supported at its upper front corner by a hanger on the track, preventing the swinging door section from swinging around or interfering or getting in the way when the door structure as a whole is moved out of the doorway and around the curve, and into fully open position at the side of the building.

It is also an object to provide certain details and features of construction and combinations tending to increase the general efficiency and desirability of a door and track construction of this particular character.

To these and other useful ends, the invention consists in the matters hereinafter set forth and claimed, and shown in the accompanying drawings, in which—

Fig. 1 is an inside elevation of a door and track construction embodying the principles of the invention, showing certain portions broken away for convenience of illustration.

Fig. 2 is an enlarged outside elevation of a section of the track.

Fig. 3 is a horizontal section of the front wall of the garage or other building, and of a portion of the side wall thereof, showing

the track in plain view, and showing the door sections and other parts in such condition that the door sections may travel or slide out of the doorway and around the curve, and into position at one side of the building.

Fig. 4 is a similar view, showing all of the door sections in fully closed position, and illustrating the condition of the track at such time.

Fig. 5 is an enlarged transverse section of the track, on line 5—5 in Fig. 3 of the drawings.

Fig. 6 is a view similar to Fig. 1 showing another form of the invention.

Fig. 7 is an enlarged detail section on line 7—7 in Fig. 6 of the drawings.

Fig. 8 is a fragmentary vertical section of a portion of one of the door sections, on line 8—8 in Fig. 6 of the drawings.

As thus illustrated, and referring to Figs. 1 to 5 of the drawings, the building may be of suitable character, having a front wall 1 provided with a doorway 2, and having an adjacent side wall 3 of the usual or ordinary character. A straight track section 4 is suitably supported over the doorway, and another straight section 5 is suitably supported on the side wall 3 of the building. A straight swinging track section 6 is hinged to the end of the section 4, at 7, as shown in Figs. 3 and 4 of the drawings. A curved track section 8 completes the continuity of the track system as a whole, being interposed between the straight section 5 and the swinging section 6 of the track. When the section 6 is swung inward into the position shown in Fig. 3 of the drawings, it strikes a block 9 that is rigid with the curved section 8, thus stopping the swinging movement of the section 6 in alignment with the ends of the sections 4 and 8 of the track.

A catch 10 is pivoted at 11 on the section 8 and is provided with a spring 12 yieldingly holding the catch in latching position. It will be seen that this catch has a beveled surface 13, which is struck or engaged by the upper portion of the swinging track section 6 when the latter is swung inward, thus forcing the latch upward, but the latch then immedi-

ately snaps downward into latching position again as soon as the upper flange or web 14 of the track section 6 engages the stop 9 previously mentioned, as shown in Fig. 5 of the drawings, thus latching the section 5 in operative relation to the sections 4 and 8 of the track. The latch is provided with a pull chain or other connection 15 for lifting the catch when it is desired to unlatch the 10 swinging track section to permit the latter to swing back into the position shown in Fig. 4 of the drawings.

The door structure comprises the sliding sections 16 and 17, and the third sliding section 18, which latter, as will hereinafter 15 more fully appear, is in certain respects a swinging door section as well. These door sections are supported by hangers 19 on the track, as shown, and the door sections are 20 hinged together by upper and lower hinges 20 (the lower hinges not shown), whereby the doors are hinged together, and they swing relatively to each other when they are moved from the doorway around the curve 25 8 and into fully open position on the track section 5 at one side of the building.

To close the door structure, the door sections are moved back into the position which they occupy in Fig. 3 of the drawings, the 30 chain 15 is then pulled to unlatch the swinging track section 6, and the door section 18 is then pulled outward into fully closed position, as shown in Fig. 4 of the drawings.

This swinging door section 18, therefore, 35 with the construction shown in the drawings, only swings inward far enough to cause the track section 6 to engage the end of the track section 8, and just enough to enable this section 18 to form the leading section as the others follow around the curve 40 into fully open position. Therefore, the door section 18 does not swing inward far enough to permit entrance between this door section and the adjacent side of the doorway, 45 and entrance is effected by then sliding the doors far enough to permit entrance between the section 16 and the other side of the doorway. For this purpose, the outer sides of 50 the door sections may have suitable handles that can be grasped to open the door structure, and the door structure may have locks or latches of any suitable character (not shown) for locking or latching the door in closed position, if such is necessary or desirable.

In Figs. 6 to 8, inclusive, the construction is similar to that previously shown and described. In this case, however, the door section 16 has a special hanger 21 that travels 60 on the track like the others, but the hanger 21 has its lower end portion connected by an arm 22 that is pivoted on the hanger body at 23 and swiveled at its other end 24 on the stem or hanger rod of one of the hangers 65 19 previously mentioned.

The door section 16, as shown in Figs. 6 and 7, has a locking bolt and latch device comprising a vertically reciprocating bolt 25 having an overhanging portion 26 to rest upon the ledge 27 at the lower end of the 70 hangar 21, this bolt having a catch 28 pivoted at 29 thereon and extending through the bolt, and provided with a hook-shaped head 30 for engaging an opening 31 in the hanger 21, whereby the door section 16 will be latched in position on the hanger 21 when the section 16 is in closed position in the doorway. A rod 32 has its upper end pivoted on the catch 28, and a compression 80 spring 33 is interposed between the under side of the catch and the shoulder 34 of the casing 35 that provides a housing and guide for the bolt. When a pull is exerted on the chain or other connection 36, attached to the lower end of the rod 32, the catch 28 is pulled down first, thus releasing the door 85 16 from its hanger 21, so that this door section can be swung inward to permit entrance to the garage or other building. The locking bolt portion 26, when in the position 90 shown in Fig. 7 of the drawings, sustains the weight of the door section 16 on the hanger 21, preventing this door section from sagging.

In order that the locking bolt and latch mechanism of the door section 16 may be operated from either the inside or the outside, a mechanism of the kind shown in Fig. 8 may be employed. This mechanism comprises a folding or swivel handle 37 mounted to move up and down in the bearings 38 and 39 secured to the outer side of the door section 16, as shown. This handle 37 can also swing or fold back against the door section 16, so that the handle will not strike the side of the wall when the doors are in fully open position. On the inner side of the door a fixed handle 40 is secured in place and provided at its upper end with a pivoted thumb piece 41, which is movable up and down. The arm 42 is movable up and down with the handle 37, and is swiveled on one portion of this handle, to permit the handle to swing or fold back, as previously explained. The lower end of the chain 36 passes through an opening 43 in the thumb piece 41 and is secured in the opening 44 in the arm 42, whereby downward movement of the handle 37 from outside the door will pull the latch 28 downward and unlatch the door section 16 from its hanger 21 in the manner previously explained. Also, downward pressure on the thumb piece 41 from inside the door will likewise unlatch the door section from its hanger, if such is necessary or desirable.

Therefore, with the construction shown in Figs. 6, 7 and 8 of the drawings, the door section 16 can be opened to permit entrance without disturbing the sections 17 and 18, 130

if such is desired. In this way the door structure serves not only as a sliding door for opening the garage doorway to the full width thereof, but a portion of the door structure serves as an ordinary entrance door to permit entrance and exit without in any way disturbing the other sections of the door structure. When the door section 16 is unlatched from its hanger 21, the arm 22 keeps the hanger 21 in proper position to be re-engaged with the locking bolt and latch mechanism, as shown in Fig. 7 of the drawings.

With this construction, entrance can be effected by simply opening the door section 16 in the manner explained; this door section 16 can then be re-closed and latched on its hanger 21 in the manner explained. The door section 18 and the swinging track section 6 can then be pulled inward from inside the building, instead of being pushed inward from the outside; and the entire door structure can then be moved out of the doorway and around the curve into fully open position at the side of the building.

Without disclaiming anything, and without prejudice to any novelty disclosed, what I claim as my invention is:

1. Sliding door construction comprising a track having straight sections disposed at an angle to each other, one section over the doorway and the other on the side of the building, all inside the building, a swinging section between the two straight sections, pivoted on the end of the straight section over the doorway in position to swing into and out of operative position to either complete or break the continuity of the track as a whole, and a sliding door structure comprising a swinging section provided with hangers to travel on said track when the swinging track section is in operative position.

2. A structure as specified in claim 1, comprising one or more sliding door sections hinged to said swinging door section and provided with hangers also traveling on said track, said swinging door section forming the leading section when the door structure is moved out of the doorway and around on to the track section at the side of the building.

3. A structure as specified in claim 1, comprising one or more sliding door sections hinged to said swinging door section and provided with hangers also traveling on said track, said swinging door section forming the leading section when the door structure is moved out of the doorway and around on to the track section at the side of the building, there being a curved track section between the swinging track section and the straight section at the side of the building, providing a curve around which all of the door hangers travel as the door structure as

a whole is moved from closed position into open position, and when the door structure is moved from open position to closed position.

4. A structure as specified in claim 1, having one or more sliding door sections hinged thereto and provided with hangers also traveling on said track, said swinging track section and swinging door section having sufficient inward swing to bring said swinging track section into operative position but preventing entrance between the swinging door section and the adjacent side of the doorway.

5. In sliding and swinging door construction, the combination of a swinging door section and one or more sliding door sections hinged together, a track system extending over the doorway of the building and along one side wall thereof, hangers for said door sections, means permitting movement of the door sections out of the doorway and around on to the track section at the side of the building, said swinging door section being the last or following section during such opening movement, and the swinging door section being the leading section when the door structure as a whole is moved into closed position in the doorway, said swinging door section having a latching connection with one of said hangers to permit swinging movement of this door section inward without disturbing the other section or sections of the door structure, and means for operating said latching connection to disconnect the swinging door section from said hanger, permitting the swinging door section to serve as a door to be opened and closed to permit entrance to and exit from the building without disturbing the other door section or sections.

6. A structure as specified in claim 5, having means whereby said latching connection is operable from outside the door.

7. A structure as specified in claim 5, having means whereby said latching connection is operable from either outside or inside the door.

8. A structure as specified in claim 5, said hangers being disposed in such position that each and every door section is supported at both upper corners thereof to prevent sagging of any door section during the sliding movement of the door structure into open position, or during sliding movement of the door structure into closed position.

9. A structure as specified in claim 5, said latching connection having means to support the adjacent corner portion of the swinging door section on the hanger, so that the swinging door section is supported against sagging when latched to its said hanger.

10. In sliding and swinging door construction, the combination of a track hav-

ing a straight section above the doorway of the building, and having another straight section at the side of the building, with a curved section between the two straight sections, a plurality of door sections hinged together and provided on each upper corner thereof with hangers traveling on said track, means whereby the entire door structure is operative to be moved out of the doorway and around the curve into open position at the side of the building, said hangers being adapted to support each and every door section at both upper corners thereof, when the entire door structure is in closed position, and means whereby the section at the side of the doorway toward which the door structure moves in closing is supported in closed position on said first mentioned track section and is adapted to be swung inward a distance to permit entrance to and exit from the building without disturbing the closed position of the other door section or sections.

11. A structure as specified in claim 10, one of said hangers having a separable connection with the swinging door section to permit said inward swing of this section, but the said separable connection being closed to support the swinging door section on the track during the opening and closing movement of the door structure as a whole.

Specification signed this 19th day of May, 1928.
